TITLE SETTING APPARATUS

Philip Schneider, Dunellen, N.J.

Application February 11, 1949, Serial No. 75,960

2 Claims. (Cl. 294—87)

1

This invention relates to improvements in tile setting apparatus. In particular, the invention is directed to an improved holding fixture for ceramic or other tile whereby a plurality of tile blocks may be temporarily secured in position during the process of tiling a wall or other surface.

The principal object of my invention is to provide a tool by which a number of pieces of tile may be securely held in position for application to a prepared surface and readily released when the tile is in place.

A further important object of my invention is to provide a tile setting device, by the use of which tile blocks may be accurately applied with respect to a surface being tiled.

A still further object of my invention is to provide a tool for tile setting by which work may be accomplished with greater speed and less fatigue than is possible using presently accepted methods of tile setting.

With these and other objects in mind my invention comprehends, in part, a rigid holding device provided with novel clamping means and adapted to hold a group of tile pieces. In some respects the apparatus of my invention accomplishes a like result for large tile as is had with flexible paper backing for smaller floor tile, wherewith a multiplicity of small tiles may be set in a single operation, the backing being removed after the tile is in position. With wall tile, the sizes of which are considerably larger than floor tile, a flexible, removable backing is not practical or desirable.

The apparatus of my invention permits secure clamping and quick release of tile pieces and may be readily manipulated by a workman fitting tile against a wall. To avoid bulging of the tile in the apparatus, which would otherwise occur by reason of the relatively thin tile section when clamping pressure is applied, I employ a series of thin, floating, guided tongues which interfit between mating tile surfaces which are perpendicular to the direction of applied pressure, and I thus avoid any tendency for the tile pieces to become displaced before the clamp is released. When the tiles are in position against a wall, the clamping pressure may be readily and easily released and the tile pieces remain secured to the wall.

The invention will be better understood by consideration of the following specification, taken in conjunction with the drawing in which:

Figure 1 is a face view of the apparatus of my invention showing tile pieces assembled therein;

2

Figure 2 is a cross-section view of the tile setting apparatus of Figure 1 taken on line 2—2 of Figure 1.

Figure 3 is an enlarged fragmentary view of the top left hand corner of my improved tile setting tool showing details of the floating tongue which interfits between tile.

Figure 4 is a cross-section view taken on line 4—4 of Figure 3.

Figure 5 is a fragmentary rear face view of my improved tile securing apparatus showing details of the clamping mechanism with the clamp open.

Figure 6 is a side elevation of the clamping mechanism, partly in cross-section, taken at the right of the clamp of Figure 5, and

Figure 7 is an end elevation of the clamping mechanism of Figure 5, partly cut away for clarity.

In Figures 1 and 2, a flat, perforated plate 10, preferably of aluminum or other light weight metal alloy provides a substantially rigid surface against which pieces of tile T may be positioned face downward. The top edge of plate 10 is bordered with a thin, angular retainer flange 12 which fastens to the back of the plate. Flange 12 projects above the plane of the plate surface for a short distance, less than the thickness of a piece of tile, and a first horizontal run of six tile blocks T may be located against the projecting portion thereof.

Below the first run of tile and spaced approximately one tile dimension A laterally apart centrally of the tile are a series of floating tongues 14 of thin metal, the positioning of which will accommodate the vertical dimension B of standard tile. This dimension for square tile may vary from products derived from different sources of supply, however in most instances of which I am aware, the tile size is a fraction of an inch under or over 4 inches. It is to be understood at this point that the invention is independent of a limitation insofar as tile sizes are concerned and likewise, while reference is particularly directed herein to ceramic tile, the apparatus of my invention may be used with any other relatively thin block of material where it is desired to clamp and de-clamp as in the case of tile setting.

The construction of tongues 14 may be more clearly understood by reference to Figures 3 and 4, each tongue being cut out and angularly formed as an integral part of a flat, rectangular slide member 15, the latter of which is movably confined against the rear surface of plate 10.

by means of a channeled guide piece 16 affixed to the back of the plate. Member 15 with tongue 14 is permitted a prescribed amount of vertical travel parallel to the plane of plate 10, within limits defined by the extremes of position of tongue 14 within the rectangular clearance aperture 17 in plate 10, so that tongue 14 may thus be positioned to accommodate a particular tile width B. Some clearance is also provided between the sides of member 15 and the channel of piece 16 so that tongue 14 may be aligned with the tile edge. I prefer to fabricate member 15 from a smooth piece of stainless steel approximately $1/64''$ thick and somewhat wider than tongue 14 so that when the tongue 14 is cut and formed therefrom, the bifurcated legs 15' extending downwardly beyond the extremity of the tongue serve to add to the stability of the assembly. Tongue 14 projects up beyond the top surface of plate 10 to adequately contact the edge of tile, but insufficient to extend beyond the tile, thereby avoiding interference with the wall to which tile is applied.

Again referring to Figures 1 and 2, below the first horizontal run of tile is a second run, a third run and a fourth run with corresponding floating tongues 14 interposed between each vertically arranged pair of tiles. Under the last run of tile is a horizontal clamping bar 20 carrying a somewhat resilient strip 21 which engages the lowermost edges of tile pieces, to become biased upwardly and exert a clamping effect there-against, as will be more fully shown later. Abutment strip 21 may be of any suitable plastic material in order that it will deform slightly when clamping pressure is exerted to compact the tiles vertically without chipping or marring the tile structure.

Tongues 14, being extremely thin, are insufficient to affect appreciably the vertical tile spacing. They do, nevertheless, compensate for any irregularity in the sides of the tile which may be present either in smoothness or angularity and, being restrained against movement vertical to the plane of plate 12, they serve as an intermediate support during tile clamping to preclude bulging or pulling away of the tile from the plate. Once clamped, the entire assembly of tile pieces will be quite stable and may be readily handled without disturbing the positioning of the tile.

Details of the clamping mechanism are shown in Figures 5, 6, and 7 wherein it will be noted that clamping bar 20 of channel section carrying the resilient abutment piece 21 is fixed to a series of three spaced carrier members 22, see also Figure 1, slidably confined in carrier guides 23 secured to plate 12. As in the construction of the flange 12 and tongues 14, it is important that clamp 20 and its associated parts do not over-extend the back surface of tile whereby interference with the wall would be evident during use. Tension springs 24, interposed between the spring posts 25 on the plate 12 and on the end of each carrier, tend to hold the clamp in its outermost position. Clamping is effected by the manipulation of handle 26 fixed to hollow shaft 27 trunnioned in a series of three bearings 28 spaced on plate 12. When handle 26 is pulled upwardly from the back of plate 12, counterclockwise in Figure 6, shaft 27 will be turned and flat springs 30 will become wrapped about the collars 31 to which they are secured, thus drawing the carrier members 22 with clamping bar 20 inwardly by interconnection therewith

10 against the effect of springs 24 to clamp the tiles in position. As handle 26 is manipulated in the direction of clamping, the spring biased pawl 32, see Figure 7, pivoted on the handle 26 will engage successive teeth of ratchet 33 fastened to center bearing 28 to lock the handle against reverse movement until it is released by pressure applied to the overhanging end 34 of pawl 32. When de-clamped, the tile pieces will be free for transfer to the prepared wall.

15 The apparatus of my invention finds its greatest utility for setting tile in large areas, the smaller areas and irregular portions of a tiled surface being necessarily fitted with single pieces. When using the apparatus for setting tile in regular block form against a prepared wall, and with the clamp fully released, the tile setter or his helper first loads the fixture in the manner hereinbefore described, taking the necessary precautions to insure precise alignment of successive runs of tile. Advantageously, the fixture will be sloped during loading with plate 10 disposed at an angle with the horizontal so that the tile pieces will tend to slide toward the thin flange 12. Care is also taken to position the tile pieces in each lateral run so that, insofar as is possible, the ends will be square and accurate and so that the vertical runs overlie the fixture to some extent. Clamping pressure is then applied and the fixture with tile is transported to the prepared surface to be fitted in place.

20 In manipulating the assembly to the wall, the fixture is oriented 90° from the position of the drawing, the clamping handle 26 being preferably at one side and auxiliary handle 35 is at the other side, with flange 12 positioned vertically at a starting surface or a vertical row of previously set tile and one of the overlying tile runs resting against a starting base of a horizontal tile run. The tile setter may work from left to right or from right to left, and when properly positioned, the back faces of the tile are pressed into intimate engagement with the prepared wall. The clamping pressure is then released, the tile remaining in position by the normal suction of cement or other adhering substance against the back of the tile, whereafter the fixture may be drawn away for re-loading, care being taken so that the flange 12 and tongues 14 slide out from between tile joints without disturbing the setting. By working with several fixtures which may be kept continuously loaded by a helper, the tile setter may cover large areas in shorter time than has heretofore been possible when working with individual tile pieces.

25 It is to be understood that the apparatus herein described is a preferred embodiment of my invention and that various changes may be made in the shape and size and arrangement of parts without departing from the scope of the invention as defined in the subjoined claims.

Having thus described my invention I claim:

30 1. In a device for securing an assemblage of tile blocks in position, in combination, a flat supporting surface member, an abutment at one edge of said member, a movable clamp at an opposite edge of said member, holding means intermediate of said abutment and said movable clamp adapted to be slidably engaged between two tile surfaces, said intermediate holding means being adjustably positionable in a direction parallel to the plane of the supporting surface member, but confined vertically with respect thereto, means

to urge said clamp to clamping position, and means to lock said clamp in clamping position.

2. In a device for securing an assemblage of tile blocks in position, in combination, a flat supporting surface member, an abutment at one edge of said member, a movable clamp at an opposite edge of said member, holding means intermediate of said abutment and said movable clamp adapted to be slidably engaged between two tile surfaces, said intermediate holding means being 10 adjustably positionable in a direction parallel with respect to the plane of the supporting surface member, but confined vertically with respect

thereto, means to urge said clamp into clamping position, means to lock said clamp in position, and means carried by said clamp urging means to release the pressure applied by said clamp.

PHILIP SCHNEIDER.
